CLIP-ON AUTOMOBILE TROUBLE LIGHT

Robert D. Kahn, Hewlett Harbor, N.Y., assignor to
Fedtro, Inc., Rockville Centre, N.Y., a corporation

Filed May 11, 1964, Ser. No. 79,930

Term of patent 14 years

(Cl. D48—20)

FIG. 1

FIG. 2

FIG. 3

FIG. 4

FIG. 1 is a front view of a clip-on automobile trouble light showing my new design;

FIG. 2 is a side view thereof;

FIG. 3 is a rear view thereof; and

FIG. 4 is a top view thereof.

The hook is shown in operating position in FIG. 1, in non-operating position in FIGS. 2 and 4 and is omitted in FIG. 3 for convenience of illustration.

I claim:

The ornamental design for a clip-on automobile trouble light, substantially as shown and described.
